UNITED STATES PATENT OFFICE.

A. J. GIBSON, OF WORCESTER, MASSACHUSETTS.

IMPROVEMENT IN SKATES.

Specification forming part of Letters Patent No. 31,797, dated March 26, 1861.

To all whom it may concern:

Be it known that I, A. J. GIBSON, of Worcester, in the county of Worcester and State of Massachusetts, have invented a new and useful Improvement in Skates; and I do hereby declare that the following is a full, clear, and exact description of the same, reference being had to the accompanying drawings, making a part of this specification, in which—

Figure 1 is a side elevation of the improved skate, representing the back part of the same in two positions. Fig. 2 is a bottom view of Fig. 1.

Similar letters of reference indicate corresponding parts in both figures.

To enable those skilled in the art to make and use my invention, I will proceed to describe its construction and operation.

A A' represent, respectively, the joint and rear parts of the skate-iron, which are made as wide as may be desired and as thick as skate-irons usually are. The curve of these irons when put together may also be made as fancy may dictate. There may be a groove made in the bottom of these irons, extending from front to rear thereof. This skate-iron may therefore be made in every respect, excepting the joint to be hereinafter explained, like common skate-irons. These irons A A' are put together by a rule-joint B, with a strong riveted pin *a* passing transversely through the center of the joint. The joint is made by forming circular enlargements on the meeting ends of the irons, which are each half as thick as the main portions of the irons. These circular portions are lapped together with the pin *a*, which allows them to move freely. The projecting portions of this rule-joint are on the upper edge of the skate-iron, leaving the lower edge continuous from front to rear.

C C' represent a divided foot-stand, which is secured to the front and back portions A A' of the skate-iron by studs or standards *b b' b'* or in any other suitable manner. This divided foot-stand represented in the drawings is made of wood and shaped to suit the fancy. The two portions C C' do not

meet, but have a space over the joint B sufficient to allow a free movement of this joint. Instead of having an elevated foot-stand, the irons A A' may be made wider and the divided stock secured immediately to the irons, or instead of the wooden stock or the divided stock a thin steel plate may be employed, which will yield and accommodate itself to the motions of the foot, or two stiff metal plates may be substituted for the wooden pieces C C'.

The joint in the irons may be made directly under the ball of the foot or at any other desired point between the heel and toe.

I do not claim, broadly, the dividing of the skate-runner into two parts, for I am aware that this is shown in Letters Patent No. 28,984, where a flexible foot-stand is used having attached to it two independent skate-runners the ends of which fit into each other by a slip-joint. In my improvement the runners cannot separate at the joint, so that the skate practically operates the same as the ordinary skate, with the additional advantage of capability of the hinge movement; but when the runners are so made that they will separate when the joint is moved, as in the patent recited, the back end of the front skate will cut into the ice and impede the user and cause liability to fall upon the ice. The reason of this is because in the act of bending the foot the rear skate-iron withdraws its support from the front iron, and the heel thereof, being thus left unsupported, drops into the ice; but in my improvement the two skate-irons support each other, no matter what their relative angle may happen to be in respect to each other.

Having thus described my invention, I claim and desire to secure by Letters Patent as an improved article of manufacture—

A skate that has its runner jointed in the peculiar manner herein shown and described and otherwise made as set forth.

A. J. GIBSON.
